16 Claims. (Cl. 260—397.2)

1

This invention relates to improvements in the process for effecting oxidation of 3-hydroxy- Δ^5 -sterols to produce the 7-oxo derivatives. The invention is particularly directed to the oxidation of cholesterol and related sterols which are valuable intermediates in the synthesis of Vitamin D.

Various methods have been described for effecting the selective oxidation of cholesterol and other sterols when in the form of their esters or similar derivatives which can be converted to an hydroxyl group and which protect it from chemical attack during the conversion of the sterol to the 7-oxo derivative.

Heretofore, the sterol derivative, such as an ester including the chloride, is dissolved in acetic acid and subjected to the oxidizing influence of chromic acid anhydride (CrO_3) which is customarily dissolved in a small amount of water and diluted with additional acetic acid since the chromic acid anhydride itself is very soluble in water and almost insoluble in acetic acid. In this manner, a reaction medium consisting of chromic acid anhydride dissolved in high percentage aqueous acetic acid of from 90% to 98% is obtained. In carrying out these oxidations, however, certain side reactions occur along with the oxidation of the sterol to the 7-oxo derivative, resulting in relatively small yields of the desired product and the use of an excessive amount of the chromic acid anhydride. Several processes have been described for carrying out these oxidations, such as found in Windaus, Ann. 520, 102 (1935), see also U. S. P. 2,098,984; U. S. P. 2,215,727 to Rosenberg & Tinker; U. S. P. 2,237,732 to Marker and British Patent 558,361 to Boots. In the Windaus, Rosenberg and Marker processes the oxidation is carried out with chromic acid anhydride in aqueous acetic acid, as described above, and the yields of the resulting 7-oxo derivative are, in each case, approximately 25% of theory. In the process of the Boots patent it was found that the yield could be materially increased if, in place of the aqueous acetic acid formerly used, acetic acid anhydride were substituted and the oxidation carried out with chromic acid anhydride for which acetic acid anhydride is a solvent. This process reduces the number of side reactions and effects a somewhat better utilization of the chromic acid anhydride. In this process a yield of from 34% to 38% of 7-oxo cholesterol acetate was obtained.

These processes are dangerous to operate, especially where a solution of the chromic acid anhydride in acetic acid anhydride is employed, for such mixture ignites spontaneously when warmed to 90° C. and the aqueous acetic acid solution of

2

the chromic acid anhydride decomposes violently at 120° C. so that extreme care must be employed in carrying out the processes heretofore described for effecting oxidation of the sterol compounds to the 7-oxo derivatives. They are wasteful of materials because the chemical attack is not specifically directed to the 7-position of the sterol molecule, causing loss of sterol as well as oxidizing agent. In the process described by Windaus, for instance, only 11% of the chromic acid anhydride is used to form the desired 7-oxo derivative and in the process of British Patent 558,361 only 23% is thus utilized, while the remainder is consumed in side reactions.

It is an object of this invention to provide a process for the oxidation of sterols to their 7-oxo derivatives which gives materially increased yields by means of providing a novel oxidation medium for said sterols which restricts oxidation almost entirely to the desired 7-position with resulting economy of sterol and oxidizing agent. It provides a process that is simple and economical to operate, and which is less hazardous than the processes previously employed.

I have found that 3-hydroxy- Δ^5 -sterol derivatives, of which class cholesteryl acetate is employed as a typical example, can be oxidized by means of metal salts of hexavalent chromium oxide such as the metal chromates including dichromates, to give improved yields of the 7-oxo sterol derivatives. The oxidation can be carried out in a medium consisting either of aqueous acetic acid or of acetic acid containing acetic acid anhydride. In this process the highest yields are obtained under anhydrous conditions, that is, where an excess of acetic anhydride is maintained throughout the oxidation. Even better yields of the 7-oxo sterol derivatives can be obtained when the oxidation with a metal chromate is carried out in the presence of air or oxygen, since I have found that, unexpectedly, molecular oxygen under these conditions is an excellent oxidizing agent for the production of 7-oxo derivatives. Furthermore, by the addition of air or oxygen the amount of the metal chromate required is materially reduced. It is also desirable to carry out the oxidation in the presence of added alkali metal acetate or similar metal salt of an organic carboxylic acid, as it has the effect of further increasing the desired 7-oxo derivatives.

50 The following examples are given to illustrate the invention. The parts used are by weight.

Example 1

42.8 parts (.10 mol) of cholesteryl acetate, melting point 114°–115° C., are dissolved in 120

parts of glacial acetic acid and 70 parts of acetic acid anhydride by warming in a stoppered vessel to 30°-35° C. 25.9 parts of sodium chromate, Na_2CrO_4 , (.16 mol, equivalent to 120% of the calculated amount) are now dissolved in the mixture under agitation and the temperature is maintained at 30°-40° C. for 48 hours, preferably while agitating. The yellow color of the sodium chromate solution gradually gives way to the clear green color of chromic oxide (Cr_2O_3) and the progress of the oxidation can be conveniently estimated by analyzing for the remaining hexavalent chromium. When not more than about 10% of hexavalent chromium is left, the reaction mass, which is a green colored magma of 7-oxo cholesteryl acetate, is diluted with 40 parts of ice to decompose the acetic anhydride and to complete the precipitation of 7-oxo cholesteryl acetate. The shiny crystals are filtered on a nutch and washed with methanol and water alternately until the crystals are colorless. Yield: 26 parts, melting point 153°-155° C. By adding part of the methanol-water washes to the initial filtrate until turbidity sets in, a secondary crop may be obtained with a yield of 3 parts and melting point 145°-150° C. The crude 7-oxo cholesteryl acetate can be readily purified by crystallization from low boiling petroleum fractions, whereby there is obtained 24.3 parts of 7-oxo cholesteryl acetate, melting point 160°-161° C. (55% of theory) and 1.3 parts of unchanged cholesteryl acetate (3% of theory); yield based on cholesteryl acetate consumed: 58% of theory.

Example 2

If, in Example 1, 40 parts of benzene or trichlorethylene or similar solvent stable to oxidation by chromates are added to the oxidation mass, the reaction time is shortened because the added solvent helps to keep the reaction mass homogeneous. If desired, the 7-oxo cholesteryl acetate may be isolated by adding a further amount of the above solvent at the end of the oxidation, and extracting the 7-oxo cholesteryl acetate by means of the solvent from the dilute aqueous-acetic acid medium. After washing of the solvent layer with water, the 7-oxo cholesteryl acetate is obtained by adding methanol and filtering of the well-formed crystals. The yield obtained is similar to that of Example 1, and the crude 7-oxo cholesteryl acetate has a melting point of 157°-160° C.

Example 3

The 42.8 parts of cholesteryl acetate in Example 1 or 2 may be replaced by 38.6 parts (.10 mol) of cholesterol, if the cholesterol is first refluxed at 120°-125° C. for one hour with 70 parts of acetic acid anhydride. Cholesteryl acetate is thus produced in situ and substantially identical yields of 7-oxo cholesteryl acetate are obtained when this solution is oxidized as in either Example 1 or Example 2.

Example 4

If desired, a sodium chromate solution can be prepared from chromic acid anhydride and soda ash in situ in the following manner:

17 parts of soda ash (.16 mol) are added gradually to a mixture of 80 parts of glacial acetic acid and 50 parts of acetic acid anhydride. At a temperature of from 50° to 70° C. the soda ash dissolves rapidly under evolution of CO_2 , and with formation of sodium acetate dissolved in acetic acid. 16 parts of chromic acid anhydride,

CrO_3 (.16 mol), are added to the solution. The red color of CrO_3 changes at once to the bright yellow color of Na_2CrO_4 . After cooling the solution to 30°-35° C., 42.8 parts of cholesteryl acetate (.10 mol) are added, dissolved in 40 parts of acetic acid and 40 parts of acetic acid anhydride, and the oxidation is carried out as in Example 1.

Example 5

If, in Example 4, the amount of soda ash is increased, the reaction mass will contain sodium acetate in addition to sodium chromate. By using 34 parts of soda ash (.32 mol), the reaction mass will contain .32 mol of sodium acetate and the yield of 7-oxo cholesteryl acetate rises to about 65% of theory.

The same result may be obtained by adding 26.2 parts of anhydrous sodium acetate to the reaction mixture in Example 1.

Example 6

If, in Example 1 or 2, the sodium chromate is replaced by an equivalent amount of sodium dichromate, $\text{Na}_2\text{Cr}_2\text{O}_7$ (21.0 parts, .08 mol), the oxidation proceeds in a similar way although somewhat more rapidly, but the yield of 7-oxo cholesteryl acetate is somewhat decreased to 50%-52% of theory.

Example 7

A solution of calcium chromate (CaCrO_4) is prepared by adding 13.3 parts of chromic acid anhydride (.13 mol) to a solution of 35.2 parts of calcium acetate monohydrate (.20 mol) in 90 parts of acetic acid anhydride and 60 parts of glacial acetic acid. The color of this solution is yellow. To the solution are added at 30° C. a solution of 42.8 parts of cholesteryl acetate (.10 mol) in 40 parts of acetic acid anhydride and 40 parts of benzene. After 24 hours at 30° C., the calcium chromate, which was originally present in theoretical quantity, has been consumed to the extent of 95%. Yield of 7-oxo cholesteryl acetate: 55% of theory.

Example 8

By replacing in Examples 1 or 2, 42.8 parts of cholesteryl acetate with 49.0 parts of cholesteryl benzoate (.10 mol) (melting point 149°-150° C., clearing point 180° C.) and conducting the oxidation at 70° C. for 60 hours, a yield of 29.3 parts of 7-oxo cholesteryl benzoate is obtained melting point 160°-161° C., clearing point 178° C. This is 58% of theory.

Example 9

By replacing in Examples 1 or 2, 42.8 parts of cholesteryl acetate with 40.4 parts of cholesteryl chloride (.10 mol), melting point 94.5°-95.0° C., and carrying out the oxidation at 40° C., 16 parts of purified 7-oxo cholesteryl chloride are obtained, melting point 141°-142° C. The yield is 48% of theory, based on consumed cholesteryl chloride.

Example 10

240 parts of glacial acetic acid, 11 parts of water and 24.3 parts of sodium chromate, Na_2CrO_4 (.15 mol, 112% of theoretical amount for oxidation) and 42.8 parts (.10 mol) of cholesteryl acetate are dissolved together in a stoppered vessel. At room temperature there occurs hardly any reaction, but by heating to 70° C. for from 60 to 80 hours the chromate is substantially consumed. The oxidation mass is worked

up as described in Examples 1 or 2. The yield of 7-oxo cholesteryl acetate is 28% of theory and 37% when making allowance for recovered cholesteryl acetate. With a larger excess of sodium chromate, about 37% of 7-oxo cholesteryl acetate is directly obtained.

Example 11

42.8 parts (.10 mol) of cholesteryl acetate are dissolved in an oxidizing mixture consisting of 400 parts of glacial acetic acid, 200 parts of acetic acid anhydride, 20 parts of sodium acetate and 21.6 parts of sodium chromate (.133 mol or 100% of the amount calculated for the oxidation). A gentle stream of air is passed through the solution, which is kept at 30°-35° C. for 48 hours, preferably under agitation. Titration for hexavalent chromium indicates that only 20% of the sodium chromate has been consumed. After working up as indicated in Examples 1 or 2, the yield of 7-oxo cholesteryl acetate is 28.7 parts, or 65% of theory, equal to 75% of theory after giving credit for recovered unused cholesteryl acetate.

Example 12

42.8 parts (.10 mol) of cholesteryl acetate are added to a solution of 200 parts of glacial acetic acid, 70 parts of acetic anhydride, 70 parts of benzene, 6 parts of sodium acetate and 5.4 parts (.033 mol, 25% of amount theoretically needed) of sodium chromate, Na_2CrO_4 , and the solution is agitated for from 60 to 80 hours at 30°-35° C. while a gentle stream of oxygen is passed through the reaction mass. Titration indicates that 90% to 95% of the available hexavalent chromium has been consumed and the mass is worked up as described in Examples 1 or 2. Yield of 7-oxo cholesteryl acetate: 19.4 parts or 44% of theory. After making allowance for recovered unused cholesteryl acetate, the yield is 58% of theory.

Example 13

A commercial sample of phytosterol (rich in alpha-sito-sterol) is converted to phytosteryl acetate, melting point 117°-120° C., by boiling with acetic acid anhydride. If this product is oxidized under conditions analogous to Examples 1 or 2, a crude oxidation product is obtained in very good yield, from which is isolated by means of repeated crystallizations from low boiling petroleum fractions a 7-oxo phytosteryl acetate, melting point 164°-166° C., which appears to be a mixture of 7-oxo sitosteryl acetates.

This process is particularly applicable to the oxidation of 3-hydroxy- Δ^5 -sterols to produce the 7-oxo derivatives where the hydroxyl group in the 3-position has been protected by an ester group including chlorine, which groups can be readily converted back to the hydroxyl radical. In addition to the esters employed in the specific examples above, the process is applicable to the oxidation of any of the aliphatic esters in which the 3-hydroxyl group has been esterified with any aliphatic acid containing up to 18 carbon atoms, such as propionic, butyric, stearic, etc.; also of aromatic esters other than the benzoate. Di-basic acids such as molanic or aromatic di-basic acids such as phthalic may also be used. Likewise, 3-hydroxy sterol-ethers such as the methyl ether may be used.

Any of the metal chromates which are sufficiently soluble to be reduced in the oxidation mass may be employed, such as the alkali metal

chromates, the ammonium chromate, calcium chromate, cobaltous chromate, manganese chromate, etc. For optimum yields a neutral chromate should be employed, or a chromate where the metal base is in excess of the chromic acid, which may be in the form of the salt of an organic acid, which is soluble in the reaction mass, such as sodium acetate, potassium acetate, sodium propionate, sodium butyrate, etc., the metal being any of those forming the chromates discussed above. In any given oxidizing system the metals of the chromate and acetate or other salt may be the same or different. Preferably the acetates or other salt are used in the proportion of 0.1 to 10 mols per mole of cholesteryl ester. A marked increase in the yield of the desired oxo derivative of sterol is obtained in this process over the yields obtained where free chromic acid is employed, even where the chromic acid is in excess of the metal base, such as in the dichromates, or with even a lower ratio of metal base to chromic acid. This may be due to the reduction in the acidic character of chromic acid by the metal base which in turn modifies the oxidizing power of hexavalent chromium. The metal chromates may be added to the reaction all at once, as distinguished from the previous use of the chromic acid anhydride which requires careful addition in small increments due to their high activity. The amount of the metal chromate required will depend on the manner in which the reaction is carried out, that is, whether oxygen (or air) is added. The amount of chromate used may vary from as much as several hundred per cent in excess of that theoretically required, to as little as from 2% to 3% of theory when oxygen (or air) is added to the reaction. Ordinarily, from 10% of theory to 200% in excess of theory will be preferred.

Either air or oxygen can be used to replace the chromate to a large degree, as illustrated in the above examples. The air or oxygen can be incorporated by agitating the solution in contact with air, by bubbling it through the mass or by carrying the reaction out under oxygen pressure. This catalytic air or oxygen oxidation requires the presence of only small amounts of hexavalent chromium salts so that the substitution of part of the chromate with air or oxygen is made possible by this invention. When using chromic acid anhydride in acetic acid anhydride, the addition of air or oxygen has no apparent effect upon the oxidation of sterols.

In order to obtain the reaction mass as a homogeneous solution in which all ingredients are dissolved, it is sometimes advantageous to add an organic solvent which is inert to chromate oxidation, such as benzene, chlorobenzene, chloroform, trichlorethylene, etc.

The best yields are obtained when the reaction is carried out in anhydrous medium, that is, where there is an excess of acetic anhydride at the end of the oxidation and after liberation of water of reaction. The beneficial effects of chromates however, as compared to the use of chromic acid itself, are evident also in a glacial acetic acid medium and in aqueous acetic acid, of as low as from 80% to 90% acetic acid content, and much increased yields of 7-oxo derivatives are obtained. Other organic acids, such as propionic, butyric, etc., and their anhydrides, may be substituted for the acetic acid in this process.

As illustrated in the above examples, the sterol ester can be prepared in the acetic acid anhy-

dride medium by refluxing for about one hour, after which the chromate may be added and the oxidation carried out without isolation of the sterol acetate. The metal chromate may also be produced in situ by reacting chromic acid anhydride with the metal acetate. This, however, should be carried out prior to the addition of the sterol to the reaction mass to avoid undesirable side reactions as experienced in the heretofore known processes wherein chromic acid anhydride is employed in place of the metal chromate.

The reaction may be carried out at any desired temperature within reasonable limits, the preferred temperatures being from ordinary room temperatures to 100° C. The speed of the reaction will of course depend upon various factors, as will be obvious to those skilled in the art, and the time required for completing the oxidation may vary from several hours to several days.

The present invention provides a process for producing the 7-oxo cholesteryl acetate and related sterol compounds from expensive raw materials such as cholesterol, in a yield approximately three times as great as that obtained by the previously disclosed methods wherein chromic acid anhydride is employed in slightly aqueous acetic acid, and in yields approximately twice as high as obtained where chromic acid anhydride is employed in acetic acid anhydride. It also permits more efficient utilization of the chromic acid, for, as the efficiency of utilization of the chromic acid in the previously described process ranges only from about 10% to 25% of theory, in the process of the present invention the efficiency of the utilization of the chromic acid is from 40% to 60% of theory in the absence of added air or oxygen, while with the addition of air or oxygen the efficiency of utilization of the chromic acid is as high as 200% of theory, based on the chromate employed, and over 300% based on the chromate consumed.

The process of the present invention provides a safe method for carrying out the oxidation of the sterol derivatives, for, whereas the previously known methods wherein chromic acid anhydride is employed are dangerous especially because a solution of CrO₃ in acetic acid anhydride ignites spontaneously when warmed to 90° C. and an aqueous acetic solution decomposes violently at 120° C., the metal chromates employed in the present process in acetic acid anhydride do not ignite at any temperature. Furthermore, the oxidation of the sterol derivatives by the present method is slow, and therefore very easily controlled.

Due to the high yield of the 7-oxo compounds, the by-products are very readily removed, and in plant operation technically pure 7-oxo cholesteryl acetate, with a melting point of 156°-159° C., may be obtained directly by filtration of the oxidation mass which is of suitable purity for chemical processing without recrystallization. The methods using chromic acid anhydride have heretofore required recrystallization of the crude 7-oxo cholesteryl acetate.

I claim:

1. A process for oxidizing an ester of a 3-hydroxy- Δ^5 -sterol to the 7-oxo derivative which comprises subjecting the sterol ester to oxidation in the presence of a metal chromate in a medium of the class consisting of acetic acid of at least 80% concentration, acetic anhydride and mixtures of the same, and with the addition of oxygen to the reaction mass.

2. A process for oxidizing an ester of a 3-hydroxy- Δ^5 -sterol to the 7-oxo derivatives which comprises subjecting the sterol ester to oxidation with a metal chromate in a medium of the class consisting of acetic acid of at least 80% concentration, acetic anhydride and mixtures of the same, and in the presence of added metal acetate.

3. A process for oxidizing an ester of a 3-hydroxy- Δ^5 -sterol to the 7-oxo derivative which comprises subjecting the sterol ester to oxidation in the presence of a metal chromate in a medium of the class consisting of acetic acid of at least 80% concentration, acetic anhydride, and mixtures of the same in the presence of a metal acetate and with the addition of oxygen to the reaction mass.

4. A process for oxidizing an ester of cholesterol to the 7-oxo derivative which comprises subjecting the cholesterol ester to oxidation in the presence of a metal chromate in a medium of the class consisting of acetic acid of at least 80% concentration, acetic anhydride and mixtures of the same, and with the addition of oxygen to the reaction mass.

5. A process for oxidizing an ester of cholesterol to the 7-oxo derivative which comprises subjecting the cholesterol ester to oxidation with a metal chromate in a medium of the class consisting of acetic acid of at least 80% concentration, acetic anhydride and mixtures of the same, and in the presence of added metal acetate.

6. A process for oxidizing an ester of cholesterol to the 7-oxo derivative which comprises subjecting the cholesterol ester to oxidation in the presence of a metal chromate in a medium of the class consisting of acetic acid of at least 80% concentration, acetic anhydride and mixtures of the same in the presence of a metal acetate and with the addition of oxygen to the reaction mass.

7. A process for oxidizing an ester of cholesterol to the 7-oxo derivative which comprises subjecting the cholesterol ester to oxidation with sodium chromate in a medium of the class consisting of acetic acid of at least 80% concentration, acetic anhydride and mixtures of the same, and with the addition of oxygen to the reaction mass.

8. A process for oxidizing an ester of cholesterol to the 7-oxo derivative which comprises subjecting the cholesterol ester to oxidation with sodium chromate in a medium of the class consisting of acetic acid of at least 80% concentration, acetic anhydride and mixtures of the same in the presence of added sodium acetate.

9. A process for oxidizing an ester of cholesterol to the 7-oxo derivative which comprises subjecting the cholesterol ester to oxidation with sodium chromate in a medium of the class consisting of acetic acid of at least 80% concentration, acetic anhydride and mixtures of the same in the presence of sodium acetate, and with the addition of oxygen to the reaction mass.

10. A process for oxidizing cholesteryl acetate to the 7-oxo derivative which comprises subjecting the cholesteryl acetate to oxidation with sodium chromate in acetic acid containing sufficient acetic acid anhydride so that an excess of the acetic acid anhydride is present throughout the oxidation.

11. A process for oxidizing cholesteryl acetate to the 7-oxo derivative which comprises subjecting the cholesteryl acetate to oxidation with sodium chromate in acetic acid containing sufficient acetic acid anhydride so that an excess of the acetic acid anhydride is present throughout the

oxidation, and passing oxygen through the reaction mass as the oxidation proceeds.

12. A process for oxidizing cholesteryl acetate to the 7-oxo derivative which comprises subjecting the cholesteryl acetate to oxidation with sodium chromate in acetic acid containing sufficient acetic acid anhydride so that an excess of the acetic acid anhydride is present throughout the oxidation, with an excess of sodium acetate being present in the reaction mass.

13. A process for oxidizing cholesteryl acetate to the 7-oxo derivative which comprises subjecting the cholesteryl acetate to oxidation with sodium chromate in acetic acid containing sufficient acetic acid anhydride so that an excess of the acetic acid anhydride is present throughout the oxidation, with an excess of sodium acetate being present in the reaction mass, and passing oxygen through the reaction mass as the oxidation proceeds.

14. A process for oxidizing an ester of a 3-hydroxy- Δ^5 -sterol to the 7-oxo derivative which comprises subjecting the sterol ester to oxidation with a metal chromate in glacial acetic acid and in the presence of sufficient acetic anhydride to completely react with all of the water liberated in the reaction so that the reaction is carried out entirely under anhydrous conditions.

15. A process for oxidizing an ester of choles-

terol to the 7-oxo derivative which comprises subjecting the cholesterol ester to oxidation with a metal chromate in glacial acetic acid and in the presence of sufficient acetic anhydride to completely react with all of the water liberated in the reaction so that the reaction is carried out entirely under anhydrous conditions.

16. A process for oxidizing an ester of cholesterol to the 7-oxo derivative which comprises subjecting the cholesterol ester to oxidation with sodium chromate in glacial acetic acid and in the presence of sufficient acetic anhydride to completely react with all of the water liberated in the reaction so that the reaction is carried out entirely under anhydrous conditions.
